UNITED STATES PATENT OFFICE.

JOSEPH W. SCHLOSS, OF NEW YORK, N. Y.

GARMENT-SUPPORTER.

No. 877,238.

Specification of Letters Patent.

Patented Jan. 21, 1908.

Application filed February 23, 1907. Serial No. 358,769.

To all whom it may concern:

Be it known that I, JOSEPH W. SCHLOSS, a citizen of the United States, residing at the city of New York, in the county of New York and State of New York, have invented certain new and useful Improvements in Garment-Supporters, of which the following is a full, clear, and exact description.

My invention relates to stiffeners for garments, and particularly to that class which are employed for stiffening lace or fabric collars, or for fastening together the different parts of a garment, or article of wearing apparel.

15 The principal object of the invention is to provide a stiffener of this class which is readily removable or replaceable when desired but which is firmly attached or fastened in place when in use.

20 A further object of the invention is to provide a device of this character, which is very cheap to manufacture, and which is strong and durable in use.

25 With these and other objects in view, the invention consists in the form of stiffener, as hereinafter set forth and shown, and finally particularly pointed out in the appended claims.

30 In the drawing: Figure 1 is a side or face view of a stiffener embodying the principles of my invention; Fig. 2 is a view of the same applied to a lace collar by means of suitable loops thereon; Fig. 3 is a view of the stiffener applied to a collar by means of buttons.

35 In wearing soft fabrics, particularly the lace or ribbon collars used by ladies, a need arises for greater stiffness than is inherent in the material in order to prevent objectionable folds and wrinkles. Such additional 40 stiffness may be secured by ribs of resilient material attached to the fabric in a suitable direction for the purpose, but these interfere with washing the fabric if permanently attached.

45 In carrying out my invention I aim to provide a stiffener which overcomes all of the above difficulties, and which is applicable to other uses, such, for example, as a fastener or link by which different parts of wearing apparel may be connected together.

50 Referring now to the drawings in which like parts are designated by the same reference sign, 1 indicates a plate or strip of resilient material, such as celluloid, and which 55 may be conveniently formed from sheet

material in a die press. The end of the plate or strip 1 is formed to constitute a hook or fastening means for attachment to a fabric or other article to be stiffened. For this purpose the strip is laterally incut near each end, as shown at 2, the incut portions having a restricted channel 3, and terminating in an eye 4. The entrance to these incut portions is rounded into the adjacent edges of the strip so as to guide and assist the entrance of a button or loop therein. In this way there is formed a pair of protuberances 5, rounded into the incut portions 2, and projecting laterally at the two ends of the strip. The width of these protuberances is reduced adjacent to the eye 4, so as to form a restricted neck 6, the ends of the strip being conveniently-slightly notched or incut for this purpose.

55 In use it is merely necessary to provide a pair of loops 7, at suitable points upon the fabric to be stiffened, and then insert the protuberances 5 through such loops, until the loops are received in the eyes 4 and embrace the reduced portion or neck 6 of each 60 protuberance. It is evident that under these circumstances the stiffener is tightly held to the fabric, not only by the engagement of the loops with the protuberances, but by the restricted channels 3 of the two 65 incut portions 2. This double engagement is sufficient to prevent accidental dislodgment of the stiffener under all circumstances. But the stiffener may be purposely removed at any time by a simple manipulation.

70 A feature of the invention lies in having the incut portions 2 extend inward from the opposite sides of the stiffener. By having the stiffeners shaped in this way they are made more secure against accidental dislodgment, because since the stiffener can only be removed by lateral movement in one direction at each end, no accidental blows or strains can wholly dislodge the stiffener if the ends are constructed to be displaceable 75 from opposite sides, rather than from the same side. In other words, strains in either 80 lateral direction are positively resisted by the fastening at one end of the stiffener and frictionally resisted by the fastener at the other 85 end under all conceivable circumstances.

90 In Fig. 3 the stiffener is shown applied to a fabric collar by means of buttons 8 thereon. The fastening of the buttons is merely pushed through the incut portions 2 of the stiffener 95 100 105 110

so as to enter the eyes 4, where they are held against dislodgment by the restricted channels 3.

In order that the loops 7 may be properly located on the collar or other device to which the stiffener is to be applied, said loops may be worked in or applied to the garment over the neck 6 of the stiffener. That is, the stiffener as a whole may be placed and held by hand against the garment and the loops worked in over the neck 6 by passing turns of the same through the eyes 4. The said loops will then be properly placed with respect to each other and to the stiffener, and the latter may be removed at any time when desired in the manner above indicated.

While my improved stiffener has been shown and described as particularly adapted for use in connection with ladies' collars, it is equally well adapted for use with belts of silk or other soft material. When so used, it will be applied in substantially the same manner as above described.

In addition to its use as a stiffener, this device may be employed as a fastener for connecting together different parts of a garment; for example, it may be used in place of a safety pin for fastening together the ends of flannel collars. When the device is used as a fastener it may be made of metal or any material having an ornamental appearance.

What I claim is:—

1. A garment stiffener comprising a strip of resilient material having an in cut portion at each end, said in cut portions being directed inward from opposite sides at the respective ends, and each in cut portion terminat-

nating in an eye, said in cut portions having a restricted channel adjacent to the eye.

2. A garment stiffener comprising a strip of resilient material having an in cut portion at each end terminating in an eye, said in cut portions each having a restricted channel adjacent to the eye.

3. A garment stiffener comprising a strip of resilient material having a laterally projecting protuberance at each end joined to the body of the stiffener by a restricted neck, said protuberance projecting in opposite lateral directions at the respective ends.

4. A garment stiffener comprising a strip of resilient material having an in cut portion at each end terminating in an eye, said in cut portions each having a restricted channel adjacent to the eye and rounding into the adjacent edges of the stiffener so as to form a protuberance, each such protuberance having a restricted neck adjacent to said eye.

5. A garment stiffener comprising a strip of resilient material having an in cut portion at each end terminating in an eye, said in cut portions each having a restricted channel adjacent to the eye and rounding into the adjacent edges of the stiffener, whereby a rounded protuberance is formed, the ends of the stiffener being notched toward said eyes to form a restricted neck for each protuberance adjacent to the eyes.

In witness whereof, I subscribe my signature, in the presence of two witnesses.

JOSEPH W. SCHLOSS.
